UNITED STATES PATENT OFFICE.

HERMAN E. HEITMILLER, OF ST. PAUL, MINNESOTA, ASSIGNOR TO WARE GRAIN BINDER ATTACHMENT CO., OF MINNEAPOLIS, MINNESOTA, A CORPORATION OF MINNESOTA.

BINDER-HEAD FOR HARVESTERS.

1,106,562.

Specification of Letters Patent. Patented Aug. 11, 1914.

Application filed February 23, 1911. Serial No. 610,339.

To all whom it may concern:

Be it known that I, HERMAN E. HEITMILLER, of St. Paul, county of Ramsey, State of Minnesota, have invented certain new and useful Improvements in Binder-Heads for Harvesters, of which the following is a specification.

My invention relates to a mechanism for securing a cord, made usually from flax fiber, around the bundle of grain, taking the place of the well known knotter mechanism usually employed for this purpose.

The object of my invention is to simplify and improve certain mechanical devices shown and described in the U. S. patent of Joseph L. Ware dated October 1, 1912, No. 1,039,853, on binder-heads for harvesters, which patent has been assigned to the Ware Grain Binder Attachment Company, a corporation, also assignee of this invention and application.

The invention consists generally,—First, in an improved means for feeding the ribbon, second, an improved mechanism for operating the knife which severs the ribbon to form the binder clips, third, an improved mechanism for operating the cord severing knife, fourth, an improved construction of the cord holder.

In the accompanying drawings forming part of this specification, Figure 1 illustrates a vertical sectional view through a portion of a binder with my invention applied thereto, Fig. 2 is a side view, partially in section, showing the mechanism for feeding the ribbon, Fig. 3 is a similar view, also in section, taken on a line substantially at right angles to the section line of Fig. 2, showing another view of the ribbon feeding device and also illustrating the means for operating the cord severing knife, Fig. 4 is a plan view, partially in section, showing the cord severing knife in its normal position, Fig. 5 is a front view, illustrating the means for operating the clip severing knife, Fig. 6 is an end view, partially in section, of the device as illustrated in Fig. 3, with the operating cam removed, showing the position of the cord severing knife operating means, Fig. 7 is a detail sectional view of the cord holder, Figs. 8, 9 and 10 illustrate the position assumed by the cord and the manner of folding the clip thereon.

In the drawing, (Fig. 1) 2 represents the deck of a binder, 3 one of the packer arms

operating through the deck in the usual way, 4 the needle, the operation of which and the packer arms is controlled by a trip lever 5. This lever is operated through mechanism, not shown, at the opposite side of the deck in the usual way in machines of this kind. 6 represents the drive shaft on which the knotter head is mounted. The frame 7 of the head has a hub 8, (see Fig. 5) that is mounted on the shaft 6 and on this frame 7 the clamp forming and folding mechanism is arranged. A disk 9 is secured on the shaft 6 and provided with cam surfaces which will be hereinafter referred to.

As shown in Fig. 1, the frame 7 has a plate 10 supporting standards 11 which carry a spool 12 on which the ribbon 13, preferably of metal, is wound. This ribbon consists of a thin strip of metal and the pieces cut therefrom are readily folded to form a clasp or binder. Rollers 14 and 15 are provided in position to receive the end of the ribbon (see Figs. 2 and 3). The lower roller 14 is mounted on one end of an arm 16 which is pivoted at 17 in the frame and a spring 18 mounted on an upright stud 19 engages the opposite end of the arm 16 from the roller 14 and holds the said lower roller toward the upper one with a yielding pressure. The upper roller 15 is journaled on a stud 20. The lower roller has a gear 21 at its inner end meshing with a similar gear 22 on the upper roller. An arm 23 is loosely mounted on the shaft of the upper roller and carries a pawl 24 which engages the gear of that roller. (See Fig. 2). A link 25 pivotally connects the arm 23 with a loop 26 that is mounted in a vertical rock shaft 27 which has bearings in the frame 7. The lower end of the vertical shaft 27 carries a horizontally operating cord severing knife 28. When the shaft 27 is rocked to swing the severing knife around into the throat of the binder head preparatory to cutting the cord the arm 22 will be swung toward the left as viewed in Fig. 2, the pawl 24 sliding on the teeth of the ratchet, and upon the return movement of the rock shaft 27 and the knife 28, the arm 22 will be swung back to its normal position and the rollers 14 and 15 will be revolved to feed the ribbon a sufficient distance to form a clip.

The upper end of the shaft 27 is provided with a pinion 29 which meshes with teeth 30 mounted on a reciprocating bar 31. This

bar is slidable in a guide way provided in the hub 8, (see Figs. 2 and 3) and is actuated by means of a pin 32 which projects into a cam track 33 formed in a collar 34 that is mounted on the shaft 6. (See Fig. 3). The cam track 33 is so formed that the bar 31 will be reciprocated at the proper time to rotate the shaft 27 to set the cord severing knife 28 in its working position 10 and operate the ribbon feeding rollers. The ribbon is fed through a slot 35 into contact with a stop 36, thus insuring clips of the same length at each operation of the machine.

15 A stationary knife 37 is mounted in the frame of the head, over which knife the ribbon is fed. A movable knife 38 is arranged above the projecting end of the ribbon and is vertically movable with respect 20 thereto and its lower edge has a groove 39 therein which is adapted to receive the upper edge of a plunger 40. (See Figs. 2 and 5). A lever 41 (see Fig. 5) is pivoted at 42 on the binder head frame and is provided at 25 one end with an anti-friction roller 43 which contacts with a cam surface 44. The lever 41 is operatively connected with the vertically moving knife 38 by a rod 45. Through this connection the knife 38 is re- 30 ciprocated vertically as the lever 31 is oscillated. This lever 41 carries jaws 46 having recessed faces 47 which coöperate with a stationary jaw 48 and grip the cord during the operation of folding the clip. The lever 35 41 is normally held in its withdrawn or retracted position by a spring 48'. The plunger 40 reciprocates in the guide-way 49 in the frame 7 and in a groove 39 in the lower end of the knife 38, the forward end 40 of the plunger engaging the clip to move it lengthwise into contact with the faces 47 of the jaws 46. The plunger 40 has an adjustable connection 50 with a lever 51 which is pivoted at 52 and is provided with an 45 arm 53 carrying rollers 54 and 55 between which the edge of the cam disk 9 is inserted. When the disk is revolved, the cam surfaces thereof will cause the oscillation of the lever 51 and a positive reciprocation 50 of the plunger. A guide 56 is preferably mounted on the plate 10 between which and the frame the lever 51 is oscillated. The cord 57, composed of flax fiber or other suitable material, is threaded through the needle 55 in the usual way and passes up to a cord holder, consisting of a disk 58 having a hub 59 fitting within a sleeve 60. A pin 61 is mounted in the sleeve and engages a groove 62 in the hub. A disk 63 has a spindle 64 loosely fitting within the hub 59 and a flat spring 65 is mounted on the frame of the binder head and attached to the spindle 64, the tension of the spring holding the disk 63 against the disk 58 with a yield-

ing pressure. Teeth 66 are preferably provided on the inner face of the disk 63 to aid in holding the cord between the disks. At a predetermined point in the formation of a bundle of grain the needle will carry the cord up around the rear of the bundle in the usual way, delivering it across the free end of the cord which is held between the clamping disks of the holder, one end of the cord being gripped in the cord holder which is free to turn in its bearings as the packers 65 force the grain against the cord until the bundle is completed, and when the needle moves to lay the other portion of the cord across the end it is gripped by the holder where it will be engaged by the clamping 80 jaws and held during the operation of folding and squeezing the clip. The operation is substantially the same as shown and described in the Ware patent above referred to and detailed description thereof is unnecessary.

When the clip has been formed and squeezed around the cord the anti-friction roller 67, mounted on an arm 68 which is secured to the shaft 6, will contact with the 90 spring 65 and push the spindle 64 inwardly and release the end of the cord, and the cord holder being held in its open position, as indicated in Fig. 7, the needle on its return stroke will lay the cord therein and the severing knife will then perform the severing operation. When the anti-friction roller 67 has passed out of contact with the spring 65 the cord holder will close, gripping the 95 cord again and the needle having returned to its normal position the parts will be 100 in proper relation to repeat the operation described.

I claim as my invention:

1. The combination, with a binder deck, 105 of a cord holder, means for packing the grain against the cord, a needle arranged to bring up the cord and lay it across the portion held by said holder, a ribbon-feeding device, including a rock shaft, and means 110 for operating the same, and mechanism actuated by said rock shaft and engaging the ribbon to feed the same, said mechanism including a ratchet device, feed rollers, and a link connecting said ratchet device with 115 said shaft, means for serving a clip from the ribbon, and means for forming a clamp around the contiguous portions of the cord.

2. The combination, with a binder deck, 120 of a cord holder, means for packing the grain against the cord, a needle arranged to bring up the cord and lay it across the end portion held by said holder, a ribbon-feeding device including an upright rock shaft 125 and means geared to said shaft for operating the same, and coöoperating rollers operatively connected with said shaft and actuated thereby and engaging the ribbon, means

for severing a clip from the ribbon, and means for forming a clamp around the contiguous portions of the cord.

3. The combination, with a binder deck, of a cord holder, means for packing the grain against the cord, a needle arranged to bring up the cord and lay it across the end portion held by said holder, a ribbon feeding device comprising upper and lower 10 rollers between which the ribbon is inserted, a rock shaft having a ratchet connection with said rollers for actuating the same to feed said ribbons, means geared to said rock shaft for operating the same, means for severing a clip from the ribbon, and means for forming a clamp around the contiguous portions of the cord.

4. The combination, with a binder deck, of a cord holder and means for packing the 20 grain against the cord, a needle arranged to bring up the cord and lay it across the portion held by said holder, a rock shaft, a ribbon-feeding mechanism operatively connected with said shaft and including feed 25 rollers, a ratchet mechanism and a link pivotally connecting said ratchet mechanism with said shaft, means for severing a clip from the ribbon, means for forming a clamp around the contiguous portions of the cord, 30 and a cord-severing knife carried by said rock shaft.

5. In a binder head, a cord holder, means arranged to bring up the cord and lay it across the portion held by said holder, jaws 35 between which a clamp is formed around contiguous portions of the cord, a cord severing knife operating beneath said jaws, an upright shaft whereon said knife is mounted, and a rack and pinion device for rotating 40 said shaft and oscillating said knife.

6. In a binder head, a cord holder, means for bringing up the cord and laying it across the portion held by said holder, means for gripping the contiguous portions of the cord, 45 a cord severing knife, disposed near said gripping means, a rotating shaft whereon said knife is mounted, a rack and pinion device for operating said shaft, a ribbon feeding mechanism operatively connected with 50 said rotating shaft, means for severing a clip from said ribbon, and means for folding the clip around the clamped portions of the cord.

7. The combination, with a binder deck, 55 of a cord holder, means for packing the grain against the cord, a needle operating

to bring up the cord around the bundle and deliver it to that portion held by said cord holder, means for feeding the metal ribbon, a reciprocating severing knife, an oscillating 60 lever operatively connected with said knife, jaws mounted on said lever, stationary jaws between which and said lever the portions of the cord are gripped and held, and means of forming the clip severed from said ribbon around the portions of the cord between 65 said jaws.

8. The combination, with a binder deck, of a cord holder, means for bringing the cord around the bundle and laying it over that 70 portion held by the said holder, jaws between which the contiguous portions of the cord are gripped and held, a ribbon feeding mechanism, a clip severing knife, an oscillating lever, a rod connecting said lever with 75 said severing knife, and means for folding the clip severed by said knife around the clamped portions of the cord.

9. In a binder head, a cord holder, means arranged to bring up the cord and lay it 80 across the portion held by said holder, a rock shaft, means for operating the same, ribbon feeding rollers adjacent to said rock shaft, said rollers being geared together, an arm loosely mounted on the shaft of one of 85 said rollers and having a pawl to engage the gear of that roller, and means connecting said arm with said rock shaft.

10. The combination, with a binder deck, of a cord holder, means for packing the 90 grain against the cord, a needle arranged to bring up the cord and lay it across the portion held by said holder, a ribbon-feeding mechanism, a clip-severing knife, an oscillating cord gripping jaw, and a connection 95 between said oscillating jaw and said severing knife for reciprocating the latter when the frame is oscillated.

11. In a binder head, a cord holder, means arranged to bring up the cord and lay it 100 across the portion held by said holder, a movable cord gripping jaw, means for feeding a metal ribbon, a ribbon-severing knife, and a rod pivotally connected with said ribbon-severing knife and with said cord 105 gripping jaw, for the purpose specified.

In witness whereof, I have hereunto set my hand this 8th day of February, 1911.

HERMAN E. HEITMILLER.
